[57] **CLAIM**

The ornamental design for an eyelet for wearing apparel, as shown and described.

DESCRIPTION

FIG. 1 is a front perspective view of an eyelet for wearing apparel showing our new design;

FIG. 2 is a top plan view thereof;

FIG. 3 is a bottom plan view thereof;

FIG. 4 is a side elevational view thereof, the opposite side is a mirror image;

FIG. 5 is a front elevational view thereof;

FIG. 6 is a rear elevational view thereof;

FIG. 7 is a front perspective view of a second embodiment of an eyelet for wearing apparel showing our new design;

FIG. 8 is a top plan view thereof;

FIG. 9 is a bottom plan view thereof;

FIG. 10 is a side elevational view thereof the opposite side is a mirror image;

FIG. 11 is a front elevational view thereof;

FIG. 12 is a rear elevational view thereof; and,

FIG. 13 is a top plan view, the broken line showing of the shoe and eyelets for wearing apparel is for illustrative purposes only and forms no part of the claimed design.
